UNITED STATES PATENT OFFICE

GEORGE D. FULL, OF WINNETKA, ILLINOIS, ASSIGNOR TO DUDLEY LOCK CORPORATION,
OF CHICAGO, ILLINOIS, A CORPORATION OF ILLINOIS

PERMUTATION LOCK FOR DOOR LATCHES

Application filed January 23, 1928. Serial No. 248,617.

This invention relates to permutation or keyless locks, and has for an object to provide such a lock adapted for use in connection with a door latch of the type commonly termed a "night latch". Another object is to provide means for preventing ascertainment of the lock's combination by the sense of feeling or by hearing the operation of the tumblers;

5 A further object of this invention is to construct the lock that it may be manipulated in light or dark with equal facility. It consists in certain features and elements of construction, in combination as herein 10 shown and described and as indicated by the claims.

In the drawings:

Figure 1 is an axial section through the lock, with the tumblers arranged in locking position, and a standard type of night latch indicated in dotted lines.

Figure 2 is an axial section showing the mechanism in unlocking position for actuating the night latch.

25 Figure 3 is a transverse section taken as indicated at the line 3—3 on Figure 1.

Figure 4 is a transverse section through the lock taken substantially as indicated at the line 4—4 on Figure 1.

30 Figure 5 is a view taken at the line 5—5 on Figure 1, showing the method of securing the lock to a door.

Figure 6 is a perspective axial disassembly of the parts of the lock.

35 Figure 7 is a face view of the dial and operating knob.

The permutation lock embodying the present invention is designed and constructed to replace and supplant the usual tumbler locks of the key-operated type used in connection with a night latch for a door. As shown in the drawings, a casing or housing is indicated at 1, preferably annular in shape and has one of its ends closed, the other end is open and is provided with an outwardly extending peripheral flange, 2, on which is mounted a cover, 3, having its outer edge spun over the flange, 2, for permanently securing it thereto. The central portion of the cover is formed to extend out-

wardly to serve as a bearing, 4, for a shaft or spindle, 5, extending into said casing and operably connected to locking mechanism as will presently be described.

The mechanism when arranged in locking position as shown in Figure 1, normally prevents axial movement of the shaft; but by rotating said shaft in certain directions to predetermined positions, the mechanism will become so adjusted to permit the shaft to be freed and moved axially until the slot or groove, 6, formed in its inner end, engages the tongue or upper end of an operating bar, 7, whereby a slight rotation of said shaft will actuate the latch indicated at 8 to unlocking position. This operating bar is centrally aligned with the shaft and with the lock assembly.

The shaft is provided with a rib or key, 9, extending laterally therefrom adjacent its longitudinal center and in radial alignment with a driving dog, 10, adjacent the inner end of said shaft, extending transversely of the slot, 6. A series of disk-type tumblers are mounted on said shaft normally positioned between the key, 9, and dog, 10, in locking position, as shown in Figure 1, and adapted to be operatively aligned on said key in lock-opening position as illustrated in Figure 2. For convenience, these tumblers may be referred to as a driving tumbler, 11, adjacent the dog, 10; an intermediate tumbler, 12, and a top tumbler, 13. Each of these tumblers is provided with a key-way, 14, adapted to be engaged slidably with said key on the shaft to permit axial movement of the same. The driving tumbler, 11, is provided with driving lugs, 11^a and 11^b, on its respective surfaces and positioned diametrically opposite each other. The intermediate tumbler is also provided with driving lugs, 12^a and 12^b, on opposite surfaces, in diametrically opposite relation. The lug, 11^a, is adapted to be engaged by the dog, 10, of the shaft, while the lug, 11^b, is positioned to drive the lug, 12^a, of the intermediate tumbler, and the lug, 12^b, is positioned to engage a lug, 13^a, on the adjacent surface of the tumbler, 13, for transmitting

80

100

rotation from said shaft to all three tumblers.

A ratchet or click wheel, 17, is positioned on said shaft adjacent the outer surface of the tumbler, 13, and is formed with a way, 18, to provide a sliding driving connection with the key, 9, of the shaft in either locking or unlocking positions. This wheel is provided with a plurality of teeth, 19, corresponding to the number of equal fractional units that the shaft may be rotated to complete a revolution, and as herein shown, the number of teeth in said ratchet is twelve. A spring, 20, is riveted to the inner wall of said casing, in position for registration with the teeth as a pawl, causing a clicking action as the shaft is rotated, to definitely indicate by sound or touch the number of units of rotation through which the shaft has been revolved. Bearing washers, 21, are positioned between the tumblers, 11 and 12, 12 and 13, and between the tumbler, 13, and ratchet, 17. A collar washer, 22, is positioned on top of the ratchet, 17, providing a seat for a coil spring, 23, which is interposed between said washer and an end plate, 24, against the inner side of said cover, 3. A shoulder washer, 25, engages the lower surface of the tumbler, 11, and supports the same in spaced relation from a fourth tumbler plate, 26. It will be noted that the washer, 22, lies in the plane of the spring, 20, and the side thereof toward said spring is reduced in size to provide clearance, while the other washers are all notched to clear said spring in assembling. The washers, 21, 22 and 25, are each provided with a pair of diametrically opposite grooves, 27, adapted to engage a pair of longitudinally extending diametrically opposite ribs, 28, formed on the inner wall of the casing to fix said washers against rotational movement. This construction obviates the transmission of any driving movement from one tumbler to another through frictional contact with an intermediate bearing washer. The coil spring, 23, acts to hold the ratchet wheel and the tumblers yieldingly in frictional engagement between their respective bearing washers, thus assuring at all times the proper alignment of the co-operating lugs of the tumblers, in their respective planes.

The fourth tumbler, which is the plate, 26, is concentrically mounted in fixed relation in the casing and is provided with a central bore, 26^a, slightly greater than the diameter of the shaft. A plurality of equally spaced notches, 30, open off the bore, 26^a; the number of said notches herein shown as six, may be varied as long as it is a multiple of the number of teeth in the ratchet which governs the number of equal angular units of rotation of the shaft. One of said notches, as indicated at 31, is larger than

the others, affording a passageway for the dog, 10, as the shaft is moved axially through said plate. The lower end of the dog, 10, is shouldered at 10^a to form an auxiliary dog, 10^b, adapted to register with any of the small notches, 30, with the shoulder, 10^a, abutting the top of said plate and preventing further inward movement of the shaft. The purpose of the small notches and auxiliary dog is to baffle and perplex anyone attempting to ascertain the combination of the lock by "feeling". The large notch, 31, is positioned preferably for convenience and simplicity, in alignment with an initial starting point of the lock, such as the enlarged node, 32, secured to the outer surface of the cover, 3. The notch, 31, may be positioned otherwise than in line with the node, 32, to obtain variations in lock "combinations". Of course it is understood that the keyways of all the tumblers must also be in alignment and register with the key, 10, to permit the shaft to be moved through said tumblers into engagement with the tongue of the operating bar, 7, for actuating the latch, 8.

Tumbler plate, 26, is supported by three integral leg members, 35, extending through the bottom of the casing and riveted over in a base plate, 36, thereby securing the plate to the casing. These leg members are shouldered at 35^a for spacing the plate in proper relation to the casing and to the shaft. This tumbler plate, 26, may also serve to retain the mechanism in a fixed unlocked position, which may be accomplished by rotating the shaft after the dog, 10, passes through the notch, 31, beyond the plate, so that the upper end of the dog abuts against the underside of the plate, and will remain in such position until the dog is again aligned with its groove, 31, to permit the shaft to be moved outwardly into locking position.

This base plate is provided with a central opening, 37, for the shank of the operating bar, 7, and is concentrically recessed at 38, in which is mounted a bearing plate, 39, against which abut the under sides of a pair of oppositely extending arms, 7^a, of the operating bar, 7. This bearing plate turns with said bar when rotated by the shaft, and serves to provide easy and free bearing contact, and overcome possible binding due to these arms, 7^a. A wireloop spring, 40, is arranged in said recess on the plate, 39, engaging said arms, and having its ends secured in the plate, 36, as shown in Figure 6. Said spring is formed so as to permit rotation of the operating bar when engaged by the shaft, and also for yieldingly returning said bar in a definite relation to the casing, so as to always insure proper alignment of the bar for engagement by the shaft

after said shaft has been released by the tumblers for axial movement.

A knob, 45, is riveted to the outer end of the shaft for conveniently rotating the same; the underside of said knob is recessed at 46 to permit the knob to be telescoped over the bearing, 4, of the cover, when the shaft is axially moved into unlocking position, as shewn in Figure 2, providing a compact arrangement. A notch, 47, is provided in the periphery of the knob for registration with the node, 32, as an initial or neutral position. Preferably the notch is radially aligned with the key, 9, and dog, 10, so that the relative positions thereof may be readily ascertained. The exposed surface of the cover may be provided with suitable graduations, and for convenience, a series of equally spaced projections, 48, are formed on said cover, positioned to correspond to the number of units of rotation provided for by the ratchet wheel, 17, and spring pawl, 20, assisting in the rotation of the shaft to exact positions when it is either light or dark. The number of projections, 48, including the node, 32, may be the same as the number of clicks of the wheel or teeth of the same, but are herein shown as five projections and the node, 32, so that the distance between these points corresponds to two clicks of the pawl and ratchet or one-sixth of a revolution of the shaft.

The opening, 51, in a wooden door, 52, or other mounting member need be only large enough to permit a sliding fit of the casing, 1. The front end of the lock is supported in a recessed bearing ring, 53, and the rear end of the lock is secured to a mounting plate, 54, by three screws, 55, spaced between the legs, 35, of the tumbler plate, 26. The height of the bearing ring may be varied to suit the thickness of the door. The mounting plate, 54, is secured at its marginal edges to the door by means of wood screws, 56.

It will of course be understood that the position of the lugs on the tumblers relative to their keyways determines the combination of the lock. These lugs which are positioned on the tumblers at points radially aligned with the teeth of the ratchet, may be positioned at any of the points other than the point supplanted by the keyway, and so may the position of the notch, 31, be interchanged with any of the notches, 30. Thus, the possible number of different combinations that may be had is relatively great.

The lock may be made for manipulation by commencing the rotation of the parts in either direction; for example the operation may be as follows: The knob, 45, is positioned with its notch, 47, aligned with the node, 32; then rotating to the right three complete turns to insure that the tumblers, 11, 12 and 13, are in driving engagement with the shaft, which results from the dog,

10, on the shaft engaging the lug, 11^a, causing the lug, 11^b, to drive the lug, 12^a, and the lug, 12^b, to engage the lug, 13^a, to rotate the respective tumblers. The shaft is now rotated in the same direction to a predetermined position at which the keyway of the tumbler, 13, is aligned with the notch, 31, in the tumbler plate, 26. The shaft is then reversed in rotation through two complete turns to the left, and the necessary portion of a third turn to align the notch, 47, with the node, 32, (the tumbler, 13, remaining in a fixed position) and a continued turn in the same direction is made to a predetermined point at which the keyway of the tumbler, 12, is aligned with the keyway of the tumbler, 13, and notch, 31, in the plate, 26. The shaft is then rotated to the right one complete turn and the additional portion of another turn to align the notch, 47, with the node, 32, (tumblers, 12 and 13 both remaining stationary) and continued turning to the right brings the parts to a predetermined position in which the keyway of the tumbler, 11, is aligned with keyways of tumblers, 12 and 13, and notch, 31. Then with the three tumblers, 11, 12 and 13 properly aligned and fixed, the shaft is reversed and rotated to the left to a predetermined position, at which position the key, 9, and the dog, 10, are in line with the ways, 14, of the tumblers and notch, 31, of the plate, 26, so that the shaft may be pushed inwardly, the key, 9, passing through the ways, 14, of the tumblers, 11, 12 and 13, and the dog, 10, passing through the notch, 31, permitting the slot, 6, in the end of the shaft to engage the operating bar, 7; then by an additional slight turn of the knob, the night latch, 8, may be released.

If desired, the lock may be maintained in open position against the reaction of the spring, 40, by permitting the upper end of the dog, 10, to frictionally engage the underside of the plate, 26. The mechanism may be thrown into locking position by turning the knob until the key and dog are aligned for withdrawing rearwardly through their respective ways and notch, then a slight turn of the shaft by the knob in either direction will destroy the setting of the tumblers.

It will now be clear that if the first three parts of the combination are known, by which the ways of the tumblers, 11, 12 and 13 may be aligned, an attempt to push the shaft inwardly will be partially permitted by the auxiliary lug, 10^b, extending into one of the notches, 30, but further movement of the shaft is prevented by the shoulder, 10^a, abutting against the top of the plate, 26. This will of course for an instant cause the manipulator to believe that the setting of the tumblers is completed, which mistake is readily noted at the attempt to turn the knob. A further attempt to locate the set-

ting for the fourth tumbler will ordinarily result in destroying the setting of the other tumblers.

It will be recognized that the provision of the projections, 48, and the node, 32, on the exposed face of the casing makes it possible for the user of the lock to read the dial in the dark entirely by his sense of touch. The index notch, 47, on the knob, 45, is readily found by feeling the periphery of the knob, and the node, 32, being more prominent than the projections, 48, indicates clearly the neutral point with which the notch, 47, is registered in bringing the parts to an initial position; preferably also the notch, 47, and node, 32, are again aligned in the final position of adjustment preparatory to thrusting the shaft inward and actuating the latch bar, 7, thereby.

20 I claim:

1. In a permutation lock for a door latch, a combination of a transversely extending operating bar operably connected to said latch, a casing, a shaft journaled therein 25 provided with a longitudinal extending guide rib, a plurality of tumblers on the shaft normally holding said shaft against longitudinal movement, co-operating means for driving said tumblers by each other, said tumblers being provided with ways, and lost motion driving connections between said shaft and one of said tumblers for moving the latter to predetermined positions of adjustment for aligning the ways with the 30 rib to permit said shaft to be moved axially for engaging said operating bar to actuate the latch.

2. In a permutation lock for a door latch, the combination of a transversely extending operating bar operably connected to said latch, a casing, a shaft journaled therein provided with a longitudinally extending guide rib, a plurality of tumblers on the shaft normally holding said shaft against longitudinal movement, co-operating means for driving said tumblers by each other, said tumblers being provided with ways, and lost motion driving connections between said shaft and one of said tumblers, 45 said driving connections comprising a dog on the shaft, axially spaced from the rib, engagable by rotation of the shaft, with a projection on one of said tumblers whereby to transmit rotation to all of said tumblers for shifting them to predetermined positions as a combination, for aligning the ways of said tumblers with said guide rib to permit longitudinal movement of the shaft for engaging the operating bar to 50 actuate said latch.

3. In a lock structure as defined in claim 2, a disk on the shaft disposed slidably over the rib and provided with a plurality of equally spaced peripheral notches, a yieldable member secured to the casing and posi-

tioned to engage said notches to assist the operator in counting the number of angular units of rotation of the shaft for positioning said tumblers at predetermined points.

4. In a permutation lock for a door latch, 70 the combination of a transversely extending operating bar, operably connected to said latch, a casing, a shaft journaled therein, adapted to be moved longitudinally for actuating said latch, a series of superimposed disk-tumblers on the shaft normally restraining such movement and adapted to be positioned by rotative adjustments of said shaft to release the same for its longitudinal movement into engagement with said bar 80 to actuate the latch, and means for retaining said shaft in latch operating position.

5. In the lock structure as defined in claim 4, said means comprising a fixed tumbler positioned in the casing and having an aperture through which the shaft is adapted to move axially, said tumbler having a notch opening off said aperture, and a dog on the shaft adapted to register with and pass beyond said notch as the shaft is moved to latch opening position, whereby a slight rotation of the shaft causes the dog to be misaligned and abut against the underside of said tumbler for retaining the shaft in latch opening position.

6. In a permutation lock for a door latch having a transversely extending operating bar, a casing, a shaft journaled therein provided with a longitudinally extending guide rib, a series of super-imposed disk tumblers on said shaft normally holding the same against longitudinal movement, said tumblers having guideways adapted to be aligned with each other to permit passage of said rib through the tumblers to free the shaft, co-operating means for imparting rotary movement from one tumbler to another, a dog on said shaft engageable with a projection on one of the tumblers for rotating all of said tumblers to predetermined positions, as a combination, whereby to align said guideways to permit the shaft to be moved into operating connection with the latch bar for actuating the latch, said disk tumblers being interposed between bearing plates held against rotation by engagement with the casing.

7. In the lock structure defined in claim 6, said co-operating means comprising transversely extending lugs on the face of said disk tumblers, a fixed tumbler mounted in the casing beyond the end of the rib on the shaft when the latter is in latch locking position, said fixed tumbler being provided with an aperture and a notch off the periphery thereof, whereby said shaft must be rotated to a predetermined position for alignment of the guide rib with the guideways of the tumblers and with the dog on the shaft positioned for registration with

the notch in the fixed tumbler to permit longitudinal movement of said shaft.

8. In a lock structure as defined in claim 6, means associated with said fixed tumbler, adapted to prevent feeling out the combination of the lock.

9. In a lock structure as defined in claim 6, means preventing feeling out the combination of the lock, comprising a series of 10 equally spaced notches opening off said aperture in the fixed tumbler smaller than said notch with which the dog is registerable but including the same as one of the series of said smaller notches, whereby longitudinal movement of said shaft will be prevented when the same is positioned with the dog 15 aligned with any of said smaller notches.

10. In a lock structure as defined in claim 6, means preventing feeling out the combination of the lock, comprising a series of 20 equally spaced notches opening off said aperture in the fixed tumbler smaller than said notch with which the dog is registerable but including the same as one of the series of 25 said smaller notches, said dog being shouldered to permit movement through any of said small notches with which it is aligned to the depth of the shoulder, while preventing movement of said shaft through 30 the fixed tumbler for operably engaging the latch bar.

11. In a permutation lock for a door latch having a transversely extending operating bar, a casing and a cover therefor provided 35 with a bearing, a shaft extending into said casing and journaled in the bearing, locking means normally holding said shaft against longitudinal movement and adapted to be operated by selective rotation of the shaft 40 to free the same for longitudinal movement into engagement with said bar for actuating the latch, a knob on the outer end of said shaft for rotating the same, said knob having a recessed portion for telescoping over 45 the bearing of the cover when said shaft is actuated longitudinally.

12. In a permutation lock which includes a shaft movable axially into operative position and rotatable for setting the locking 50 mechanism which normally blocks said axial movement, an external knob on said shaft and a dial associated with said knob, said dial and knob having certain irregularities of form which the operator may identify by 55 his sense of touch alone and which serve as index means in the rotative setting of the knob.

13. In the combination defined in claim 60 12, said irregularities including a series of features disposed at equal angular intervals around the dial, one of said features being more prominent than the others, and the knob having a single irregularity disposed for registration with said features of the 65 dial.

14. In the combination defined in claim 12, said irregularities comprising a series of projections on the dial disposed at equal angular intervals, one of said projections being more prominent than the rest, and the 70 knob having a notch in its periphery adapted to register with said more prominent projection when the shaft is rotated to final position in which it is free for axial movement.
